UNITED STATES PATENT OFFICE.

JAMES G. BASTIAN, OF SHELTON, NEBRASKA.

DESIGN FOR A COMBINED HIGH AND NURSERY CHAIR.

Application filed June 30, 1927. Serial No. 22,614. Term of patent 14 years.

To all whom it may concern:

Be it known that I, JAMES G. BASTIAN, a citizen of the United States, residing at Shelton, in the county of Buffalo and State of Nebraska, have invented a new, original, and ornamental Design for Combined High and Nursery Chairs, of which the following is a specification, reference being had to the accompanying drawing, forming a part hereof.

Fig. 1 is a perspective view taken from the front, and Fig. 2 is a perspective view taken from the rear, showing my new design.

I claim:

The ornamental design for a combined high and nursery chair, as shown.

JAMES G. BASTIAN.
